UNITED STATES PATENT OFFICE.

ROY L. BURD, OF CHICAGO, ILLINOIS.

PISTON PACKING-RING.

1,092,201.

Specification of Letters Patent. Patented Apr. 7, 1914.

Application filed May 6, 1913. Serial No. 765,750.

To all whom it may concern:

Be it known that I, Roy L. Burd, a citizen of the United States, residing at Chicago, in the county of Cook and State of Illinois, have invented certain new and useful Improvements in Piston Packing-Rings, of which the following is a specification.

My invention is designed more particularly for use in connection with pistons of explosive gas engines, though it will be obvious from a consideration of the detailed description and drawing that it is likewise applicable to many other forms of pistons and similar constructions where metallic packing is desired. As is well known to those familiar with explosive and expansion engines, where a metallic packing ring is required, the piston is circumferentially grooved at one or more points and a split packing ring fitted snugly within the groove, with its meeting ends sufficiently separated to permit expansion of the ring under heating. The opening, however, provides a path for the gases or fluids from one side of the piston to the other, which steadily increases with wear, thereby materially lowering the efficiency of the engine and ultimately requiring the repairing of the piston, as is well known to those familiar with this class of machines. Various means have been adopted or suggested for obviating this difficulty, one of the most common of which is the use of a plurality of rings in which the splits or openings are located as nearly as may be on opposite sides of the piston. While this ameliorates the difficulty to some extent, the construction permits the fluids to pass the first ring and by traversing the groove to the other side of the piston, escape through the opening of the second ring. It has also been proposed to join or bridge the ends of the ring in various ways and by different devices to prevent the passage of fluids through the cut.

My invention belongs to this latter class of ring construction and has certain advantages over those heretofore employed, which will be apparent from the drawing and detailed description.

While I have illustrated and described specifically the preferred form of my invention, I have done so for the purpose of exemplification only, for it will be apparent that the invention may be embodied in other forms; for the scope of the invention reference is to be had to the following claims,

in which I have endeavored to point out the same in such terms as to distinguish it from the prior art, so far as is known to me without, however, relinquishing or abandoning any portion thereof.

Referring now to the accompanying drawings, Figure 1 is an elevation of a packing ring embodying the preferred form of my invention; Fig. 2 a fragmentary view on an enlarged scale showing the joint after the ring has worn considerably; Fig. 3, is a section through the joint of the ring on the plane of the line 3-3 of Fig. 4 on an enlarged scale; Fig. 4 is a view of the same taken at right angles to the plane of Figs. 1 and 2; and Fig. 5 is a perspective showing the meeting ends of the ring and the bridge or coupling device detached.

The same characters of reference are used for the same parts wherever they occur in the several views.

The shape of the various parts is best shown in Fig. 5, in which it is seen that the meeting ends A, A' are undercut at B, B' and rabbeted upon opposite sides, as at C, C', forming a rectangular shoulder, D, D' which is secant to the outer periphery of the ring, a tongue E, E' being left intermediate the shoulders upon each end of the ring. The piston ring may be formed in any of a variety of ways, but preferably by casting a hollow cylinder of gray iron or suitable metal which is chucked in a lathe, turned and bored, and the rings cut therefrom of the necessary width and thickness. The rings are then ground on the sides to finished size, preferably on a magnetic chuck, and split. The ring is then sprung together in circular form, ground to finished diameter, and a set of straddle mill cutters, used to rabbet the opposite corners of the outer faces of the ends, forming the rectilinear shoulders D, D' referred to above, and the undercutting of the tongues will be done in the same setting. By these very simple operations, the packing ring proper is completed.

The bridge piece or coupler is preferably formed of a metal somewhat softer than that of the ring, as for example, of brass, for a reason which will appear later, and where the coupler is small, it may be stamped out of sheet metal and struck up to the required shape. In case the ring and coupler are large, however, the former can be made to advantage by milling out from a suitably

shaped bar. The completed bridge or coupler comprises the side members H , H' which are curved on their outer edges to conform to the curvature of the packing ring, and rectilinear on their inner edges, which are adapted to fit within the rabbets formed upon the ends of the ring and seat upon the shoulders D , D' thereof. A tie-bar or cross-piece J connecting the members H , H' extends beyond the plane of the rear edges of the side members, and when the bridge is in operative position, occupies the cross channel formed by the undercutting of the ends of the ring at B , B' , as above described.

The ring is assembled with the piston in much the usual manner, the bridge piece, however, being adjusted to the ends of the ring after it is slipped into the groove provided for it in the piston. It will be seen that with a ring constructed according to my invention, leakage directly past the opening or around the back of the ring is prevented, and the bridge is maintained in proper contact with the wall of the cylinder by the pressure of the ring ends, and is therefore independent of the gas pressure within the cylinder. As the ring wears, the coupler is fed outward against the cylinder wall by the resilience of the ring, the shoulders on the ends of which act against the side members of the coupler, as seen in Fig. 2 of the drawing and as the ring opens by wear the coupler, being of softer material, is forced to wear and maintains the fit against the wall of the cylinder. On the other hand, the tie-bar passing behind the reduced ends of the tongues, prevents the coupler being forced out by the pressure and thereby wearing faster than the ring itself. Furthermore, the tongues of the ring are always protected by the coupler and the walls of the piston groove, and therefore the danger of breaking them off is avoided.

By reason of the simplicity of the construction and the nature of the few operations required, piston rings may be made according to my invention at a low cost of manufacture and used much longer than heretofore, before renewal is required.

I claim:

1. A split packing ring for pistons and the like, having the ends thereof rabbeted on their convex faces to form shoulders, a coupler comprising a member fitting upon the shoulders and a portion extending under the ends of the ring whereby both outward and inward movement of the bridge piece relative to the ring ends is limited.

2. A split packing ring for pistons and the like, the meeting ends of which are cut away to form shoulders on the same plane secant to the outer circumference of the ring, and a coupling having members with straight inner edges adapted and arranged to overlie said shoulders, and a portion extending beneath the meeting ends of the ring.

3. A split packing ring for pistons and the like, having the opposite edges of the convex faces of its ends rabbeted to form longitudinal shoulders, a coupler comprising a pair of longitudinal members fitting upon said shoulders, and a cross-member extending beneath the ends and securing the longitudinal members together.

4. A split packing ring for pistons and the like, the ends of which are rabbeted on their exterior edges to form shoulders cut away interiorly, a coupler having longitudinal members adapted to rest upon said shoulders, and a cross-member connecting the same and adapted to underlie the cut-away portion of the ends.

5. A split packing ring for pistons and the like, having its outer edges rabbeted to form longitudinal shoulders in a common plane secant to the outer circumference of the ring and under-cut to form a transverse groove or passage formed partly in each end of the ring, and a coupler comprising a pair of longitudinally extending members adapted to fit within said rabbets, and a transverse member adapted to extend beneath the ends of the ring within said groove.

ROY L. BURD.
